TRANSPORTATION SEAT OR SIMILAR ARTICLE

Sanford S. Golden, West Los Angeles, and Nick G. Stasinos, El Segundo, Calif.; said Stasinos assignor to said Golden

Application April 10, 1957, Serial No. 45,676

Term of patent 14 years

(Cl. D15—11)

Fig. 1.

Fig. 2.

Fig. 3.

Fig. 4.

Fig. 1 is a front perspective view of a transportation seat showing our new design, taken from the left side of the seat with the seat in an upright position;

Fig. 2 is a front perspective view of the transportation seat, also taken from the left side, but with the seat in a reclined position;

Fig. 3 is a front perspective view of the transportation seat taken from the right side with the seat in its upright position; and

Fig. 4 is a rear elevational view of the transportation seat showing our new design.

We claim:

The ornamental design for a transportation seat or similar article, substantially as shown.
